UNITED STATES PATENT OFFICE.

RUFUS BARRUS STICKNEY, OF SOMERVILLE, MASSACHUSETTS.

DESIGN FOR A BOTTLE.

SPECIFICATION forming part of Design No. 15,593, dated December 2, 1884.

Application filed August 14, 1884. Term of patent 14 years.

To all whom it may concern:

Be it known that I, RUFUS BARRUS STICKNEY, a citizen of the United States of America, residing at Somerville, in the county of 5 Middlesex, of the Commonwealth of Massachusetts, have invented and produced a new and original Design for a Bottle, of which the following is a specification, reference being had to the accompanying drawings, of which—
10 Figure 1 is a front elevation, Fig. 2 a longitudinal section and Fig. 3 a bottom view, of a bottle containing such design.
The nature of such design is defined in the claims hereinafter presented.
15 The body A of the bottle is the frustum of a polygonal pyramid, the bottom or base being polygonal, and by preference hexagonal. From this base the sides are spirally beaded from the bottom to the neck B, which may be
20 substantially cylindrical to its upper part, and there be suitably flanged or beaded, as represented at a. The body has on its external surface three spiral beads, b c d, arranged like the threads of a "three-threaded screw,"

each being continued in a spiral about the 25 said body from its bottom to its top. The design is not confined to such a number of the beads, as any other suitable number may be employed in carrying it out.

The leading features of the design are the 30 pyramidal form and the spiral beading of the body of the bottle.

I claim—

1. In a design for a bottle, as represented and hereinbefore described, the body A, pyramidal in form and having the spiral beading, as set forth.
2. The design for a bottle, as represented and hereinbefore described, consisting of the body pyramidal and spirally beaded from its 40 base to the neck, and of the neck cylindrical from its bottom upward, and flanged or beaded at top, substantially as set forth.

RUFUS BARRUS STICKNEY.
